CLAIM

The ornamental design for a base rail bumper as shown and described herein.

DESCRIPTION

FIG. 1 is a front perspective view of a base rail bumper;
FIG. 2 is a back perspective view thereof;
FIG. 3 is a front view thereof;
FIG. 4 is a back view thereof;
FIG. 5 is a right view thereof;
FIG. 6 is a left view thereof;
FIG. 7 is a top view thereof;
FIG. 8 is a bottom view thereof; and,
FIG. 9 is a perspective view of four base rail bumpers of FIGS. 1-8, as shown in a surrounding environment.
The broken lines shown in the figures are for the purpose of illustrating the surrounding environment of the base rail bumper, and form no part of the claimed design.

1 Claim, 6 Drawing Sheets
